CLAIM

The ornamental design for an adjustable angle curling iron, as shown and described.

DESCRIPTION

FIG. 1 is a perspective view of the adjustable angle curling iron showing our new design;

FIG. 2 is a right side elevation view of the adjustable angle curling iron of FIG. 1;

FIG. 3 is a left side elevation view of the adjustable angle curling iron of FIG. 1;

FIG. 4 is a front elevational view of the adjustable angle curling iron of FIG. 1;

FIG. 5 is a rear elevational view of the adjustable angle curling iron of FIG. 1;

FIG. 6 is a top plan view of the adjustable angle curling iron of FIG. 1;

FIG. 7 is a bottom plan view of the adjustable angle curling iron of FIG. 1; and,

FIG. 8 is a perspective view of the adjustable angle curling iron shown in a position of use.

(Continued)

In the drawings the broken lines represent portions of the adjustable angle curling iron which form no part of the claimed design.
